UNITED STATES PATENT OFFICE.

HERMANN PARDON, OF CREFELD, GERMANY.

MACHINE FOR DRAWING IN WARP-THREADS.

SPECIFICATION forming part of Letters Patent No. 700,075, dated May 13, 1902.

Application filed September 20, 1900. Serial No. 30,588. (No model.)

To all whom it may concern:

Be it known that I, HERMANN PARDON, weaver, a subject of the Emperor of Germany, residing at No. 209 Inraterstrasse, Crefeld, in 5 the Kingdom of Prussia and Empire of Germany, have invented certain new and useful Improvements in Machines for Drawing in Warp-Threads, of which the following is a full, clear, and exact description.

10 This invention has relation to improvements in machines for drawing in warp-threads.

The machines of this class hitherto in use are built with the reed in a vertical position, 15 and the knives employed for threading up move in an arc around the vertical knives from front to back. The disadvantage of this arrangement, however, is that the vertical reed prevents the warp behind it from being seen, so that when threading up the person operating the machine is inconvenienced in detecting mistakes which in complicated work easily occur. The omission to thread up one of the warp-threads is often difficult 20 to determine, and where the machine is worked by one person, as is usually the rule with the class of machine above described, the subsequent drawing through of a forgotten or missed thread is a complicated and difficult 25 operation with the vertical reed.

30 By the present improvement the reed is horizontally arranged in the machine for the purpose of enabling the work to be readily seen by the operator, whereby mistakes which may occur are immediately detected and rectified.

To this end the invention consists in the construction and arrangement of parts, as will be hereinafter described and particularly 35 claimed.

In the accompanying drawings, Figure 1 is a front view of a machine fitted with the present improvement; Fig. 2, a longitudinal section thereof on the line A B of Fig. 1; Fig. 45 3, a cross-section through the machine on the line B B of Fig. 2, and Figs. 4 to 7 are various positions of the knives.

The numeral 1 indicates the warps, which hang at the back of the part 2 of the machine and upon which the warp-threads are wound and stretched by a weight 5, attached to the lower beam. The part 2 is carried by

two horizontal cross-beams 3 and firmly attached to the standards 4 of the machine. The reed 6, with its wire-slots 7, is preferably 55 attached to the under side of the two top cross-bars 3. For this purpose small angle-pieces 8 are provided, which are firmly screwed either to the standards 4 or to the under side of the top cross-bars 3 and admit 60 of the reed being removed. The reed may be conveniently secured in place by small wooden wedges or the like. The reed 6 thus lies horizontally in the frame of the machine, while the knives 9 and 10 move up and down 65 vertically thereto. To this end the knives are secured to a frame composed of bars 11 and 12 and adapted to be raised and lowered by means of a treadle 13. Attached to the vertical bars 12 of this frame in any suitable 70 manner are two rods 14, parallel to each other and to the horizontal. On these rods 14 slides a guide-frame 15 for the knives, the plane of which is vertical to the central plane of the warp and of the reed. To the vertical middle portion of this frame 15 is attached a cord 75 16, which passes over a pulley 17 and carries a weight 18.

As already stated, the frame 11 12 rises and falls. For the purpose of guiding the frame 80 parallel slots 19, vertical to the warp, are cut in the part 2 of the framing, which allow sufficient play to the bars 11 both above and below. The upward motion of the frame 11 12 is effected by means of two straps 20, attached at one end to the tops of the vertical bars 12 and at the other to the quadrant lever-arms 21 22. The automatic downward motion is caused by two tension-springs 24, attached to the part 2 of the frame by means 85 90 of eyes 23.

The knives 9 and 10 are so mounted in the frame 15 as to be adjustable horizontally and parallel either closer together or farther apart. To this a number of interchangeable washers 95 32 are provided in the hollow arms of the frame 15, which carry the knives 9 and 10, and which may be screwed up with the knives either on the right or left hand side thereof when the knives are inserted, as occasion may 100 require.

The two quadrant lever-arms 21 and 22 are both keyed fast upon the same rod 25. This rod 25 is supported by and rocks on springs

26 at the front and upper end of the part 2 of the framing. One of the lever-arms (the arm 22) has an arm 27 on the rod 25 and extending in the opposite direction to the quadrant. 5 To this lever-arm is attached a cord 28, connecting it with the movable end of the treadle 13. The cord 28 passes over pulleys 29, fixed to the standards 4.

The operation of the present improvements 10 or the whole machine is as follows: Assuming that the knives 9 and 10 are in the position relatively to the reed shown in Fig. 4, a warp-thread is drawn from the warp 1 beneath the frame 11 and 12 and laid in the 15 notch 31 of the lower knife 10. The treadle 13 is then depressed by the foot, drawing down the cord 28 and the lever-arm 27, the quadrant-levers 21 and 22, straps 20, and frame 11 12, together with the rods 14, which carry 20 the frame 15, and the knives 9 and 10 moving upward. During this time the top knife 9 is lifted out of the hollow space between the reed-wires 7, and the lower knife 10, the 25 point of which lies closely against the top knife 9, moves from below into the same hollow space and draws the warp-thread 30 through with it. The highest position of the knives 9 and 10 is shown in Fig. 6. As will be seen, the loose end of the warp-threads 30 is brought to the upper surface of the reed 6

or threaded through it. On the descent of the knives 9 and 10, which takes place when the foot is removed from the treadle 13, the knife-frame 15 is automatically shifted onward along the rod 14. Under the action of 35 the weight 18 the point of the knife 9 as the frame 11 and 12, with its attached parts, is automatically drawn down by the tension-springs 24, which is contradistinction to the point of the lower knife 10, does not lie close 40 against the knife 10, inclosing a space one wire wide between it and the bottom knife 10 and advancing the frame 15 one split of the reed in the direction of the arrow 32.

What I claim, and desire to secure by Letters Patent, is—

In a machine for drawing in warp-threads, the combination with a frame, of a reed horizontally arranged therein, the vertically-movable knives arranged one above the other, and 50 means for operating said knives, and the bottom knife having a notch for the reception of the warp-thread, substantially as specified.

In witness whereof I subscribe my signature in presence of two witnesses.

HERMANN PARDON.
